US00D593531S

(12) **United States Design Patent**
Lee et al.

(10) **Patent No.:** US D593,531 S
(45) **Date of Patent:** ** Jun. 2, 2009

(54) **PORTABLE PHONE**

(75) Inventors: **Ji-Young Lee**, Seoul (KR); **Seung-Min Park**, Seoul (KR); **Chang-Hwan Hwang**, Goyang-Si (KR)

(73) Assignee: **Samsung Electronics Co., Ltd.**, Suwon-Si (KR)

(**) Term: **14 Years**

(21) Appl. No.: **29/322,940**

(22) Filed: **Aug. 14, 2008**

(30) **Foreign Application Priority Data**

Jun. 12, 2008 (KR) 30-2008-0025059

(51) **LOC (9) Cl.** **14-03**

(52) **U.S. Cl.** ..... **D14/138 AD**

(58) **Field of Classification Search** ..... D14/137, D14/138 R, 138 AA, 138 AB, 138 AC, 138 AD, D14/138 C, 138 G, 147, 191, 203.1–203.8, D14/218, 244.247–248, 341–347, 432, 439, D14/455–456, 496; D10/65, 78, 104; D13/168; D18/7; 455/556.1, 566, 575.1, 575.3; 345/169
